Specification for Design.

Patented Jan. 2, 1917.

Application filed July 10, 1916. Serial No. 108,478. Term of patent 3½ years.

To all whom it may concern:

Be it known that I, GEORGE P. ITTIG, a citizen of the United States, residing at Bridgeport, county of Fairfield, State of Connecticut, have invented a new, original, and ornamental Design for Chop-Dishes or Similar Articles, of which the following is a specification, reference being had to the accompanying drawing, forming part thereof.

Figure 1 is a plan view of a chop dish showing my new design, and Fig. 2 is a side elevation corresponding therewith.

What I claim is:

The ornamental design for a chop dish or similar article, substantially as shown.

In testimony whereof I affix my signature.

GEORGE P. ITTIG.
